APPARATUS FOR FORMING CONCRETE PIPES

Filed Jan. 22, 1925

Patented Apr. 5, 1927.

1,623,539

UNITED STATES PATENT OFFICE.

ALPHONS HORTEN, OF BEERLIN-WILMERSDORF, GERMANY.

APPARATUS FOR FORMING CONCRETE PIPES.

Application filed January 22, 1925, Serial No. 4,015, and in Germany January 23, 1924.

This invention relates in general to concrete pipes and to arrangements for producing such pipes. The object of the invention is to provide pipes which consist of cheap material and to provide apparatus that enables such pipes to be made in large quantities at very low costs for labor and power.

A feature of the invention consists in a pipe made of concrete in which is embedded 10 a cylindrical reticulated member which may consist of wire netting. Another feature of the invention consists in an arrangement for rotating the reticulated member on a contractile core while soft concrete is flung 15 against it from without. The core is spaced from the reticulated wire member by spacing members which may be attached to the interior of the reticulated member or wire netting, or to the exterior of the contractile 20 cylindrical core.

The internal diameter of the concrete pipe is enlarged at one end and a ring-shaped internal groove is formed in the enlarged 25 internal wall for the purpose of preventing packing, that is stuffed into the joint between two pipes, from being worked out in the course of time by the constriction and expansion of the pipes caused by changes of 30 temperature. A feature of the invention consists in forming the said internal ring-shaped groove by means of a contractile ring.

A further feature of the invention consists of a concrete flinger comprising a cylindrical concrete container with a nozzle at 35 its one end, a piston for driving the concrete through the nozzle and means for flinging the concrete from the nozzle against the rotating core covered with the reticulated concrete holder. A further feature of the invention consists in means for moving the concrete flinger along the core and reticulated member as it revolves. In accordance with 40 the invention means are provided for removing the revoluble core with a concrete pipe cast thereon from the concrete flinger to a place where the pipe is allowed to dry. This removing means consists of a trolley which travels on a rail or rails and has a coupling 45 member journaled in it that can be attached and conveniently detached from a driving shaft. Further features of the invention 50 will appear hereinafter.

The invention is illustrated in the drawing 55 in which—

Fig. 1 is a more or less diagrammatic ele-

vation partly in section of the arrangement for producing concrete pipes.

Fig. 2 is a section on an enlarged scale of the trolley for removing a cast pipe and of 60 the top end of the contractile core with the coupling device for coupling the latter to a vertical driving shaft.

Fig. 3 is a horizontal section through the core and a reticulated concrete holder. In 65 this figure the spacing members for determining the gap between the reticulated member and the core and a segment of concrete pipe are in evidence.

Fig. 4 is a section through one of the blades 70 of the revolving concrete flinging device that flings the concrete from the nozzle of the concrete container against the exterior of the revolving core.

Fig. 5 is a cross-section of a contractile 75 or divisible ring for forming an internal ring-shaped groove and sleeve with an enlarged diameter at one end of the concrete pipe.

Fig. 6 is a top view of Fig. 5. 80

Fig. 7 is a section through a joint between two finished pipes, and

Fig. 8 is a sectional view of a modified means for throwing the concrete from the nozzle of the container to the revolving core. 85

The illustrated apparatus for producing concrete pipes consists of parts rotated by a revolving vertical shaft 2 and of a concrete flinging apparatus adapted to be moved up and down on a vertical reciprocating rack 90

3. The revolving pipe holder consists of a vertical shaft or rod 4 provided at the top with a coupling member consisting of a fork 5 and key 6 and having a collar 6^a at its bottom end upon which rests a plate 7. The 95

contractile core may consist of four hollow metal segments 8, 9, 10, 11 whose bottom ends rest upon the plate 7 and which, when they are assembled around the central shaft 4 may be driven apart by a cross-shaped member 100

12 inserted between the segments at their top end as shown in Figs. 2 and 3. The arms of the cross 12 are wedge-shaped, the narrow edges of the wedges being at the bottom of the cross. Attached to the circumference of 105

the cross is a ring 13 whose internal diameter is smaller at the top than at the bottom so that a shoulder 14 is produced which is above the bottom end 15 of the cross 12. By this means the cross-shaped wedge 12 can be 110

driven down beyond the top edges 17 of the hollow segments 8, 9, 10, 11 of the core as

shown in Fig. 2 and the top edges of the segments are lodged firmly between the outer ends of the cross and the ring 13. A cross-shaped wedge similar to 12 is placed on the 5 plate 7 with its sharp or narrower edges directed upwardly so that when a flanged collar 18 is urged downwards against the top cross 12 by a wedge 19, that passes through slots in the collar 18 and the vertical shaft 10 4, the four hollow segments 8, 9, 10, 11 are driven apart until their top edges engage with the widened internal part of the ring 13 while their bottom external edges are pressed against the internal ring 20. This 15 ring may consist of four parts 21, 22, 23, 24 which are held together by any suitable means on the plate 7, but are detachable from the latter so that the sections 23, 24 may, after the core consisting of the parts 20 8, 9, 10, 11 is removed, be drawn inwards whereupon the parts 21, 22 may also be drawn inwards and removed from the end of the concrete pipe formed as hereinafter more fully described. The bottom end 25 of the vertical shaft 4 is journalled in a foot-bearing 26 which may be raised and lowered a slight distance by any suitable means in a supporting plate 27. When the finished pipe is to be removed the foot-bearing 26 is lowered 30 so that the end of the shaft 25 may be moved past the collar 28 in the supporting plate 27 as hereinafter more fully described. Arranged above the top end of the revolute core are rails 29 which support the rolls 35 30 of a trolley 31. This trolley, as seen in Fig. 1, is a U-shaped member with a wedge-shaped yoke 32. The yoke has a slot 33 so as to form two lateral fingers or cheeks adapted to enter beneath the bottom edge 40 34 of the head 5 and to support this head with the shaft 4 and the parts surrounding it. After the trolley 31 has been brought into position to support the head 34 the wedge 6 is removed and the core with the 45 pipe cast as hereinafter more fully described may then be rolled away on the rails 29.

Peripheral bars 36, 37, 38, 39 are placed between the hollow segments 8, 9, 10, 11 as shown in Fig. 3 and the afore-described 50 cross-shaped wedge 12 is tightened down so as to firmly hold the segments 8, 9, 10, 11 as described above. Then a reticulated member such as a length of wire-netting 35 is placed round the core as indicated in Figs. 55 1, 2 and 3. A gap is maintained between the wire netting 35 and the core by means of spacing members 40 which may be attached either to the core 8, 9, 10, 11 or to the wire netting 35. The core is now rotated by means of the driving shafts 1 and 2 and concrete is squirted or flung against the rotating core by means of a concrete flinger which will now be more fully described.

65 The concrete flinger is shown mounted

on brackets 41, 42 which in turn are attached to a vertical reciprocating rod 3 guided in guide members 43, 44, 45. Attached to the bracket 42 is another bracket 46 at whose bottom end is journalled a revolving member comprising blades 47 which have concave surfaces as shown by the section of a blade illustrated in Fig. 4. The blades are rotated past the nozzle 48 of a cylinder 49 in which is shown a piston 50. Said piston is pushed downward at a constant speed by a threaded piston rod 51 so as to squirt out the soft concrete 52 in the cylinder 49. As the concrete is squirted out it is struck by the blades 47 and flung against the rotating core covered with the wire netting 35 that constitutes a concrete holder. As the core rotates the concrete flinger is raised and lowered so as to cover all parts of the rotating core with concrete. The piston rod 51 is driven to and fro by a nut 53 rotated by a motor 54 through bevel wheels 55, 56. When the piston 50 is withdrawn from the cylinder 49, the latter can be re-charged with soft concrete through a hopper 57. The surface of the pipe is made smooth by a wire 58 and a scraper 59 which cut away all the concrete that extends beyond a certain distance from the core.

After a pipe has been cast in the manner described the core is uncoupled from the vertical shaft 2, the foot bearing 26 is lowered and then the core with the pipe is rolled to a place where the pipe is allowed to set and dry. The cross-shaped wedge 12 is then removed so that the hollow segments 8, 9, 10, 11 can be pulled inward and removed. The sections 23, 24 of the ring 20 are then pulled inwards and subsequently the sections 21, 22, of the ring are also removed. A pipe with an embedded cylindrical wire network and an end or sleeve of enlarged diameter, as shown in Fig. 7, is thus produced, the sleeve of enlarged diameter having an internal ring-shaped groove 60. The small end 61 of another pipe can then be inserted into the enlarged end and packing material 62 may be stuffed in. The packing material is prevented from being dislodged through slight movements of the ends of the pipes by the ring-shaped internal groove 60.

The spacing members 40 may be small protuberances on the hollow metal segments 8, 9, 10, 11 which are integral with the segments or they may be temporarily loosely attached to the segments so as to remain in the internal wall of the pipe when the core is removed, or they may consist of small blocks of concrete or the like attached to the wire netting and remaining in the tube when it is finished.

The rotary blades 47 of the concrete flinger may be substituted by a nozzle 63, Fig. 8, that directs a jet of air past the concrete ejecting nozzle 48 and a further nozzle 64 that di-

rects the jet of concrete against the revolving core.

I claim:—

1. In an apparatus for producing concrete pipes, the combination with a vertically disposed revoluble core adapted to support a reinforcement, of a vertically movable concrete flinger-device comprising a cylindrical concrete container, a nozzle at one end of the container, a piston movable within said container for forcing soft concrete through said nozzle, and revolving blades disposed below said nozzle for flinging the concrete driven therethrough against the concrete reinforcement revoluble with said core.

2. In an apparatus for producing concrete pipes, the combination of a vertically disposed revoluble core adapted to support a reticulated concrete reinforcement, a vertically movable supporting frame, means for guiding said frame, a concrete flinger-device mounted on said frame and comprising a cylindrical concrete container, a nozzle at one end of the container, a piston movable within said container for driving soft concrete through said nozzle, means for moving said piston in alternate directions at a constant speed, and revoluble blades arranged in proximity to said nozzle for flinging concrete forced therethrough against the reinforcement revolving with said core.

3. In an apparatus for producing concrete pipes, the combination with a cylindrical vertically disposed revoluble core adapted to carry a concrete reinforcement member, of a

vertically movable supporting frame, guiding means therefor, a concrete flinger-device mounted on said frame and comprising a cylindrical concrete container, a nozzle at one end of the container, a piston movable within said container at a constant speed for driving soft concrete through said nozzle, and a blade-carrying rotary member disposed in proximity to said nozzle for catching and flinging the concrete forced therethrough against the reinforcement member carried by said core.

4. In an apparatus of the character described, the combination with a vertically disposed revoluble core adapted to carry a reticulated concrete reinforcement member, of a concrete flinging-device comprising a container having a discharge nozzle at one end, a piston movable within said container adapted to force concrete through its nozzle, motor-driven means for moving said piston in opposite directions at a constant rate of speed, a support for said concrete container and said piston driving means, means for guiding said support along a line of movement parallel with said revoluble core and a revoluble blade-carrying member fixed to said support subjacent the nozzle of said concrete container for catching and flinging the concrete forced therethrough against the reinforcement member as the latter is rotated with said core.

In testimony whereof I have affixed my signature

ALPHONS HORTEN.
